UNITED STATES PATENT OFFICE.

HERMANN LEMP, OF LYNN, MASSACHUSETTS, ASSIGNOR TO GENERAL ELECTRIC COMPANY,
A CORPORATION OF NEW YORK.

CONDENSER.

No. 920,561.

Specification of Letters Patent.

Patented May 4, 1909.

Application filed January 16, 1906. Serial No. 296,422.

To all whom it may concern:

Be it known that I, HERMANN LEMP, a citizen of the United States, residing at Lynn, county of Essex, State of Massachusetts, have invented certain new and useful Improvements in Condensers, of which the following is a specification.

This invention relates to condensers for steam engines, and has been especially designed for steam automobiles, in which air-cooled surface condensers are used. As ordinarily constructed, such a condenser comprises a large number of tubes of small bore connected in multiple between two headers. Sometimes two or three of these units are put in series with each other. To enable the tubes to be cleaned by a cleaning rod, the headers must be provided with removable plugs opposite the ends of the tubes, or else with a plate that can be taken off to give access to the tubes. In either case, a large number of screw plugs or screw bolts must be taken out. In the operation of steam automobiles, there is great difficulty in separating the lubricating oil from the steam, so that the condenser soon clogs up with oil and grease, and when the steam is very hot this deposit is liable to carbonize. This makes the cleaning of such a condenser a very disagreeable and dirty piece of work, and one which the owner of a steam carriage would not wish to undertake himself. In addition to the unpleasantness of the job, it is a tedious one, requiring from one to two days steady work to complete it.

The object of my invention is to simplify the construction of a condenser of this type, and render it easy to clean when clogged up. In place of a large number of small tubes in multiple, I use a few tubes of larger bore, provided with radiating gills like those used in the radiators of gasoline motor cars. I have preferably three tubes, each bent in zigzag form in the same plane and connected at each end to a small header. The three units are placed parallel and their several lengths are staggered to give a better cooling effect. The exhaust steam is introduced at the top and the water of condensation is carried off at the bottom. No circulation pump is needed, as the back pressure from the engine is sufficient to force the water back into the tank. Before entering the condenser, the exhaust steam passes through an oil separator which deprives it of most of its oil and

grease. When the condenser is to be cleaned, two of the units are shut off by means of specially designed plugs, and live steam is admitted from the boiler, thereby thoroughly blowing out all accumulations from the unit that is left open. By shifting the plugs, each unit can be blown out in turn. The operation is speedy and of such a character that any automobile owner can readily undertake it.

In the accompanying drawing, Figure 1 is a diagrammatic view of an engine, flash boiler, water tank and condenser with the necessary piping, valves, etc. to constitute a complete system; Fig. 2 is a front elevation of the condenser on a larger scale; Fig. 3 is an end view of the same; and Fig. 4 is a sectional view of one of the headers showing the cleaning plugs in position.

The engine 1 is of any suitable construction, and is shown connected by a chain 2 with a sprocket 3 on the driving shaft 4 of an automobile. A pump 5, driven by the engine, supplies water from a tank 6 to a boiler 7, also of any suitable construction, though preferably a flash boiler. Steam is taken from the boiler to the engine through a main 8 controlled by a throttle valve 9. The exhaust steam passes from the engine through the pipe 10 to an oil separator 11, of any suitable construction, and thence to the condenser 12, whose lower end is connected by a pipe 13 with the water tank.

The condenser is composed of two headers 14 and a number of tubes 15 connected thereto in multiple. The preferable number of tubes is three, since a condenser of this class must not be too deep from front to back, in order to permit a good circulation of air. Each tube is of fairly good size, say three-fourths of an inch in diameter, and of such length as may be needed to make the desired size of condenser; preferably about twenty-five or thirty feet. Each tube is bent in a zigzag fashion in the same plane, making 100 preferably six and a half return bends. From end to end the tube is covered with radial gills 16, and at each end it has a flange 17 to enable it to be attached to a short branch or neck 18 on the header, by means 105 of a gland 19.

The short branches or necks 18 are preferably three in number and staggered as shown, so that when the tubes are connected thereto the corresponding bends in adjacent 110

units do not lie in the same horizontal planes, but come opposite the spaces between them. Opposite the end of each tube and in line therewith is an opening in the header, closed 5 by a screw plug 19.

Between the units are placed vertical spacing strips 20 and surrounding the entire condenser are two straps or ties 21 whose ends are connected by a bolt 22. Transverse 10 bolts 23 are passed through the ties and the spacing strips between the several lengths of the tubes, so that the whole structure is firmly clamped together and will withstand the jars to which it is subjected in service.

15 The exhaust steam is conducted into one end of the upper header and the water of condensation is conveyed away from the lower header to the tank.

For the purpose of cleaning the condenser, 20 means are provided for admitting live steam into it. One way of effecting this is to connect the exhaust pipe with the steam main by means of a short pipe 24, provided with a stop valve 25; a check valve 26 being inserted 25 in the exhaust pipe back of the point of connection. By opening this stop valve the condenser can be cleaned of water at any time. When thought necessary on stopping the carriage the boiler pressure may be reduced by blowing the steam into the condenser where it will be condensed, without loss of water. Should the condenser become clogged with oil or grease, it can be cleaned by live steam in the following manner: 30 Two of the screw plugs 19 are removed from the upper header, and in place of them are screwed in plugs 27, having the same thread as the others but provided with a cylindrical extension 28 adapted to fit snugly 35 into the end of the condenser tube, and serve as a stopper therefor. The drip cock 29 is then opened, or, if preferred, one of the screw plugs in the lower header corresponding to the plug 19 in the upper header is 40 taken out. The live steam valve 25 is then opened and the tube that is not shut off by the cleaning plugs 27 can be thoroughly blown out. By shifting the cleaning plugs one at a time, all three tubes can be isolated 45 successively and cleaned. The entire operation occupies but a few minutes, and is not by any means so disagreeable as the method of cleaning by hand that is necessary in the case of condensers of the ordinary construction. 50

55 In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure 60 by Letters Patent of the United States, is—

1. In a steam automobile, the combination of an engine for driving the automobile, a boiler for supplying steam to the engine, a condenser for the exhaust steam, a conduit leading from the engine to the condenser, a 70 conduit between the steam space of the boiler and the exhaust conduit for supplying live steam, to the latter to be blown through the condenser, and means for shutting off a portion of said condenser to cause the steam to 75 blow through another portion.

2. The combination with a surface condenser, of means for blowing live steam through the same, and means for shutting off a portion of said condenser to cause the steam to 80 pass through the other portion.

3. The combination with a header having openings, of tubes connected with said header in line with said openings, and screw plugs adapted to fit said openings and provided 85 with extensions to enter and close said tubes.

4. In a steam automobile, the combination of an engine for driving the automobile, a boiler, a conduit for supplying steam from the boiler to the engine, a surface condenser 90 for the exhaust steam comprising a series of tubes, a conduit leading from the engine to the condenser, a conduit connecting the steam space of the boiler with the exhaust conduit for supplying live steam to the latter to be blown through the condenser tubes, and means for shutting off one or more of the tubes to cause the steam to blow through the others. 95

5. In a steam automobile, the combination of an engine for driving the automobile, a boiler, a steam supply pipe leading from the boiler to the engine, a throttle valve in said pipe, a condenser for the exhaust steam, an exhaust pipe leading from the engine to the condenser, a valved pipe leading from the steam pipe at a point between the boiler and the throttle valve to the exhaust pipe to supply live steam to the latter to be blown through the condenser, a valve in the exhaust pipe between the engine and its junction with the valved pipe, and means for shutting off a portion of said condenser to cause the steam to blow through another portion. 105 110 115

6. In a steam automobile, the combination with a condenser composed of a plurality of bent tubes connected to headers, of a pipe for conveying live steam to the upper header, and means for shutting off any one 120 or more of said tubes.

7. An air-cooled surface condenser comprising headers, a series of tubes connecting the headers, openings in the headers opposite the ends of the tubes, removable plugs 125 for normally closing said openings which may be removed to permit the insertion of other plugs to shut off communication between the header and the tubes, and plugs adapted to be so inserted which are provided 130

with extensions that enter and close the adjacent ends of the tubes.

8. An air-cooled surface condenser comprising an upper header, a lower header, a series of zigzag tubes connecting the headers and arranged so that corresponding lengths are staggered, radiating gills on the tubes, openings in the header opposite the ends of the tubes, and removable plugs for closing

the openings some of which are provided with cylindrical extensions to enter and close the ends of said tubes.

In witness whereof, I have hereunto set my hand this thirteenth day of January, 1906.

HERMANN LEMP.
